CLAIM

The ornamental design for an air conditioner, as shown and described.

DESCRIPTION

1. Air conditioner

1.1 : Perspective

1.2 : Front

1.3 : Back

1.4 : Left

1.5 : Right

1.6 : Top

1.7 : Bottom

1.8 : Perspective

1.9 : Front

1.10 : Back

1.11 : Left

1.12 : Right

1.13 : Top

1.14 : Bottom

1.15 : Perspective

1.16 : Front

1.17 : Back

1.18 : Left

1.19 : Right

1.20 : Top

1.21 : Bottom

1.22 : Other type of view

1.23 : Enlarged

Reproduction 1.1 to 1.7 show the subject design before its change, reproduction 1.8 to 1.14 show an intermediate state in which the bottom vane is opened horizontally after its change, and reproduction 1.15 to 1.21 show the state in which the bottom vane is fully opened after its change; reproduction 1.22 is a reference view indicating an enlarged portion and reproduction 1.23 is an enlarged view showing the portion circled in reproduction 1.22; the broken lines in all reproductions and the circles represented by the dot-dashed line in reproductions 1.22 and 1.23 form no part of the claimed design; reproduction 1.23 is a reference view

(Continued)

that shows the enlarged bottom vane of the subject design and illustrates how it operates by means of the broken lines.
